UNITED STATES PATENT OFFICE.

THOMAS A. TAYLOR, OF BONHAM, TEXAS.

ROTARY STORE STRUCTURE.

Application filed February 27, 1926. Serial No. 91,108.

This invention relates to store sales or dispensing devices.

In self service stores such as the well known "Piggly-Wiggly" trouble has been experienced and loss sustained by reason of dishonest customers stealing goods from the shelves, it being impossible to effectively watch all customers except at a prohibitive expense for salaries of clerks to be stationed 10 at each set of shelves. In fact, to properly watch all customers would require practically as many clerks as would be needed in a store of the kind in which the customers are served by clerks and thus one of the important objects of self service stores, decrease of salary or pay roll expense, would be negated.

The principal objects of the present invention are to provide an improved store arrangement and apparatus therefor whereby the customers may be all easily kept under observation; to provide for the elimination of a customer desiring some particular article having to traverse a long series of aisles 25 after entering the store before they can leave; and to eliminate the necessity of a customer carrying a heavy parcel from place to place in making a number of purchases.

With the above and other objects in view 30 as will be hereinafter apparent, the invention consists in general of certain novel details of construction and combinations of parts hereinafter fully described, illustrated in the accompanying drawings and specifically 35 claimed.

In the accompanying drawings like characters of reference indicate like parts in the several views, and:

Figure 1 is a plan of a portion of a store 40 equipped in accordance with this invention.

Figure 2 is an elevation of the dispensing device and its driving mechanism, the view being partly in section to show the construction.

Figure 3 is a detail sectional view of a foot 45 step bearing for the dispensing device.

Figure 4 is a diagram plan of a typical store arrangement wherein several dispensing devices are used.

In the embodiment of the invention here 50 illustrated there is shown a store room 10 having walls or partitions 11. Of course this room is provided with the usual floor 12 and ceiling 13. Arranged in such store room is one or more dispensing units indicated in general at 14. Each of these units

has a vertical central supporting shaft 15 having its upper end journalled in a bearing 16 supported on a beam 17 secured to the ceiling, the lower end of the shaft being journalled in an anti-friction foot step or thrust bearing 18. At the lower end of the shaft is a series of radially disposed stirrups 19 which support the inner ends of beams 20. Similarly, at a suitable distance above the beams 20 are rafters 21 which are supported by braces 22. Between the rafters is arranged a polygonal drum 23 having a bottom 24 resting on the beams and a top 25 resting on the rafters. This top is in the form of a large grooved wheel and around this wheel or top passes a cable 26 forming a belt which also passes around a small grooved wheel 27 fixed on a jack shaft 28 having its upper end journalled in a bearing 29 at the ceiling while adjacent the wheel 27 the shaft passes through and is journalled in a beam 30 extending from end to end of the store room. Adjacent the upper end of the jack shaft there is fixed a belt pulley 31 which is connected by a belt 32 with the driving pulley of a motor 33 suitably supported on a bracket 34. By this means the drum is slowly rotated as long as the motor is running.

Projecting from the drum are vertically extending partitions 35 between which are arranged shelves 36 on which the goods to be sold are placed.

Of course these drums may be of any suitable size and number and a typical store arrangement for several such drums is shown in Figure 4. In this figure it will be seen that several dispensing units are employed, these being arranged in line and having partitions 37 between adjacent units and between the units and the walls at the front and back of the store. The store entrance and exit 38 is here shown at the left of the front and extending rearwardly from a point adjacent this entrance and exit is an interrupted railing 39 dividing the space to the left of the units into a sales room and an exit passage, the space to the right of the units being suitable for storage. In the sales space may be arranged one or more cashier's and observer's desks 40 as well as a manager's desk 41 and one or more sales stands 42 for articles in bulk requiring weighing or measuring. Also, where meats are sold, there may be a butcher's department at the rear of the store provided in

the usual manner with a showcase 43, block 44 and refrigerator 45. The routes for customers are shown by arrows and it is obvious that in serving one's self it is merely necessary to step in front of a dispensing unit and remove the goods from the shelves as they pass around. Of course, where more than one unit is employed each may be devoted to a particular line or lines of goods. For instance, in a grocery, one unit may be for canned goods, another for sauces, flavors and other bottled goods, another for soaps, washing powders and other laundry supplies and so on.

It is to be clearly understood that the invention is not confined to the exact arrangement of store shown in Figure 4 since it is obvious that such arrangement will vary in details in accordance with the size and shape of the store, the character of the business and its volume, and many other factors controlling such details. Accordingly the arrangement here shown is merely to be understood as a general type of the arrangement for all stores.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is

desired to include all such as properly come within the scope claimed.

Having thus described the invention, what is claimed as new, is:

1. In a rotatable dispensing device of the type described, a vertical rotatable shaft, end bearings therefor, a dispensing drum carried by said shaft, a circular top wall for the drum of a diameter slightly less than the diameter of the drum forming a belt pulley, a rotatable jack shaft disposed above the drum adjacent its peripheral edge, outwardly of the belt pulley and mounted in ceiling supported bearings, a relatively small pulley on the lower end of the jack shaft alined with the aforesaid belt pulley, a belt inclosing the pulleys and a motor for operating the jack shaft having belt connection with the jack shaft adjacent its upper end.

2. In a rotatable dispensing device of the type described, a vertical rotatable shaft, end bearings therefor, a dispensing drum carried by said shaft, a circular top wall for the drum of a diameter slightly less than the diameter of the drum, said top wall being annularly grooved to form a pulley and driving means for the drum including a pulley alined with the top wall of the drum and disposed within the marginal edge of the drum, and a belt connection between the pulley and the top wall pulley.

In testimony whereof I affix my signature.

THOMAS A. TAYLOR.
